(57) **CLAIM**

The ornamental design for a clothes cord quick fastening lock, as shown and described.

DESCRIPTION

FIG. 1 is a top, front perspective view of a clothes cord quick fastening lock showing my new design;

FIG. 2 is another perspective view thereof;

FIG. 3 is a front elevation view thereof;

FIG. 4 is a rear elevation view thereof showing the hole through which a cord may be placed;

FIG. 5 is a right side elevation view thereof, the left side is a mirror image;

FIG. 6 is a bottom plan view thereof; and,

FIG. 7 is a top plan view thereof.

The broken lines in FIGS. 1 and 2 are for purposes of illustration only and form no part of the claimed design.
